CONSOLE FOR ELECTRONIC EQUIPMENT

William F. Dalton, Fishkill, N.Y., and Rudolph H. Koepf,
Orange, Conn., assignors to International Business Ma-
chines Corporation, New York, N.Y., a corporation
of New York

Filed Dec. 23, 1959, Ser. No. 58,783

Term of patent 14 years

(Cl. D26—5)

FIG. 4

Des. 190,862

PAGE 2

FIG. 2

FIG. 3

FIG. 1 is a front perspective view of a console for electronic equipment, showing our new design;

FIG. 2 is a right side elevation, the left side being substantially a mirror image thereof and

FIG. 3 is a rear elevational view thereof.

Portions of the drawings are shaded and lined to indicate contrast in appearance.

We claim:

The ornamental design for a console for electronic equipment, substantially as shown and described.
